(57) **CLAIM**

The ornamental design for a testing device for tires, as shown and described.

DESCRIPTION

1. Testing device for tires

1.1 : Front

1.2 : Back

1.3 : Left

1.4 : Right

1.5 : Top

1.6 : Perspective view (front, top, left)

1.7 : Perspective view (back, top, right)

1.8 : Reference view (front)

The bottom of the design is flat and unadorned, and thus disclaimed. In FIG. 1.8, the broken line showing of wheels and tires is included for the purpose of illustrating portions of the “article” that form no part of the claimed design.
